BAILER

Thomas J. Hamilton, Oklahoma City, Okla., assignor to Phillips Petroleum Company, a corporation of Delaware

Application November 8, 1937, Serial No. 173,468

4 Claims. (Cl. 166—19)

This invention relates to improvements in bailers which have been primarily designed for bailing oil wells. More specifically it relates to mechanical equipment for bailing and removing sand or other particles from oil wells.

Heretofore bailers have been provided wherein the interior chamber of the bailer was kept under a vacuum, which chamber upon the landing of the bailer on the bottom of the well hole was opened to cause an inflow into the chamber of the well liquid having in suspension sand and silt. Such bailers, while having certain advantages, are disadvantageous in that no provision is made for washing away the particles and debris which are clogging the sand particles around the well hole. With the above mentioned type of bailer, as well as in the conventional type of bailer, the bailer lands in the debris in the bottom of the well without having cleaned the well hole above the bottom of the well. The debris that is caused to enter the barrel of the bailer is only that debris which is ahead of or beneath the bailer. The debris which is opposite the sides of the bailer remains in close contact therewith and should there be any material settling or caving such types of bailers may become stuck in the well.

An object of the present invention is to provide an improved bailer and oil sand washer wherein the bailer carries with it a supply of fluid under high pressure which fluid is released on the landing of the bailer on the bottom of the well and causes a washing and agitation of the sand particles forming the wall of the well. By releasing fluid pressure in the well, the discharged fluid will enlarge the cavity in the debris which is penetrated and formed by the bailer so that there is less danger of the bailer sticking or becoming frozen in the well.

A further object of this invention is to provide an improved bailer which will loosen tightly packed cavings, sand, silt, wax and other residues collected in the bottom of the well or accumulated along the sides of the well or on the sand faces.

A still further object of the invention is to provide an improved bailer which has a simple and efficient means for dumping or removing the material from the bailer when removed from the well hole.

A still further object of the invention is to provide an improved bailer which has a simple and effective means for releasing the pressure fluid from the chamber when the bailer strikes the bottom of the well hole.

A still further object of the invention is to pro-

vide an improved bailer in which considerable jarring action can be effected within the bailer to jar the bailer loose in the hole if it should become stuck therein.

A still further object of the invention is to provide an improved bailer in which pressure fluid in a chamber is discharged near the top of the bailer and directly into the side walls of the well hole.

With the foregoing and other objects in view which will be made manifest in the following detailed description and specifically pointed out in the appended claims, reference is made to the accompanying drawing for an illustrative embodiment of the invention, wherein:

The drawing is a vertical sectional view through the entire bailer showing the same in a well hole and before the pressure fluid has been released.

Referring to the accompanying drawing wherein similar reference characters designate similar parts throughout, the improved bailer is shown as comprising a two part structure, an inner section or gas chamber 1 and an outer section or collecting chamber 2 with the two sections being concentrically arranged and the inner section spaced from the inner side walls of the outer section. The outer section is closed at the bottom thereof by a sleeve member 3 which has a flapper valve 4 mounted on the top thereof. The sleeve member 3 is connected to the outer section by either screw threads or lugs and is removable from the outer section 3 to dump the contents of the bailer after it has been pulled to the surface from the bottom of the well.

The top of the outer section is internally screw threaded at 5 to receive the sleeve member 6 which is both internally and externally threaded on its lower end at 7 and 8 respectively. The external threads screw into the threads 5 on the upper end of the outer section while the internal threads 8 on the sleeve 6 receive the screw threaded upper end 9 of the inner section 1 and thus holds the inner section in place within the outer section. The upper end of the sleeve member 6 is externally screw threaded at 10 to receive the cap or head piece 11 which is internally screw threaded at 12 and screws on the upper end of the sleeve 6. The cap member 11 has an opening 13 in the top thereof in which is slidably mounted a weighted rod 14. The rod 14 has an eye 16 on the top thereof in which is attached the sand line or cable 17 for raising and lowering the bailer from or into the well hole. On the lower end of the rod 14 is a head portion which prevents the rod from being pulled through

the opening 13 in the cap portion. The head portion 15 is confined within a chamber 18 in the top of the outer section.

The gas chamber or inner section of the bailer is constructed pressure tight and made in three sections 19, 20 and 21. The lower section 19 is closed on the bottom and has a pressure fill valve extending thereinto from the exterior of the outer section. Connected by screw threads to the upper end of the lower section 19 is the section 20 which has a valve seat 23 in the upper portion thereof. The upper section 21 is screw threaded to the middle section and has a valve seat 24 in the upper portion thereof. A double acting valve 15 having a stem 25 with heads 26 and 27 on either end thereof and a spring 28 is mounted so that one end of the spring rests on the valve seat 23 while the other end is seated on a shoulder on the valve 26. The coil spring 28 keeps the valve head 27 seated on the seat 23 thus making a pressure tight chamber 30 in the lower end of the inner section. The rod 14 and head 15 are adapted to fall by the weight of gravity, striking the upper valve head 26 and forcing the same downwardly against the tension of the spring 28 which seats the valve head 26 on the seat 24. When this occurs the valve head 27 is lowered, out of contact with the seat 23 and communication is established between the pressure chamber 30 and the chamber 29 in the upper portion of the inner section. Jet members 31 connect into the wall of the section 21 and discharge the pressure gas through ports 32 in the outer section into the formation.

To operate the bailer it is necessary to fasten the sand line or cable 17 to the eye 16 for lowering the same into the well. But first the chamber 30 must be filled with high pressure gas which is accomplished by a man standing on the derrick floor attaching a high pressure gas line to the fill valve 22 and filling the chamber 30 to the pressure desired. The action of the spring 28 and the pressure of the gas in chamber 30 will force the valve head 27 to seat on the seat 23 and close the chamber 30 off. The bailer is now ready to be lowered into the well and as the line 17 begins to bear the weight of the bailer in lowering, the rod 14 will be pulled upwardly through the opening 13 in the cap member until the head 15 contacts the cap portion.

When the bailer comes to rest on the bottom of the well, the rod 14 and head 15 will continue to move downwardly due to its weight and being slideable in the cap 11 until it contacts the valve head 26, forces the same to seal with the seat 24 which in turn opens the lower valve 27. This will allow the gas in chamber 30 to be discharged into the upper chamber 29, through the jets 31, ports 32 and thus into the well hole formation. The discharged gas will break loose the caked particles of sand and silt and clean the walls of the well. The jetting action of the gas through the ports 32 will create a vacuum in the annular space 33 between the gas chamber 30 and the outer section 2 of the bailer body and in the lower part of the bailer above the flapper valve 4. The pressure in the bailer thus being lower than the well hole pressure, the sand and silt particles will rush through the bottom of the bailer 3, unseating the flapper valve 4, in order to equalize the pressure outside of the bailer and that within the evacuated low pressure area inside the bailer.

When the gas has been completely discharged from the gas chamber, the chamber will be filled with sand and silt and the bailer will be ready to be raised to the surface of the ground. The weight of the sand and silt in the body of the bailer will force the flapper valve in the bottom of the bailer to close. The rod 14 and head 15 will be pulled upward upon the bailer's being lifted, and the spring 28 will force the valve head 27 to seal with the seat 23 and thus keep the sand and silt from entering the gas chamber 30. The bailer may be emptied upon reaching the surface of the ground by removing the bailer bottom 3 which is attached to the bailer body by lugs or a threaded joint.

It is to be understood that the form of my invention, herewith shown and described, is to be taken as a preferred example of the same, and that various changes in shape, size, and arrangement of parts may be resorted to, without departing from the spirit of my invention or the scope of the subjoined claims.

Having thus described my invention, I claim:

1. A bailer comprising an outer tubular section, an inner tubular section mounted in the outer tubular section, said inner tubular member being closed at both ends to form a gas tight chamber for holding fluid under pressure, means for releasing the pressure fluid upon the landing of the bailer on the bottom of the well hole and discharge means for the pressure gas comprising a jet member mounted in the wall of the inner section and discharging through the wall of the outer section.

2. A bailer comprising an outer tubular section, an inner tubular section mounted in the outer tubular section, said inner tubular member being closed at both ends to form a gas tight chamber for holding fluid under pressure, means for releasing the pressure fluid upon the landing of the bailer on the bottom of the well hole and discharge means for the pressure gas comprising a jet member mounted in the wall of the inner section and discharging through ports in the wall of the outer section.

3. A bailer comprising an outer tubular section, an inner tubular section mounted in the outer tubular section, a space between the two sections, said inner tubular member being closed at both ends to form a gas tight chamber for holding fluid under pressure, means for releasing the pressure fluid upon the landing of the bailer on the bottom of the well hole and discharge means for the pressure gas comprising a jet member mounted in the wall of the inner section discharging through the space between the inner and outer sections and then through ports in the wall of the outer section.

4. A bailer comprising an outer tubular section, an inner tubular section mounted in the outer tubular section, said inner tubular member being closed at both ends to form a gas tight chamber for holding fluid under pressure, said chamber being closed at the top by a sliding valve member, means for releasing the pressure fluid upon the landing of the bailer on the bottom of the well hole, comprising a sliding rod member in the top of the bailer to unseat the valve and discharge means for the pressure gas leading through the wall of the outer tubular section.

THOS. J. HAMILTON.
